(Continued)

Primary Examiner — Ralf Seifert(74) *Attorney, Agent, or Firm* — Steven E. Jedlinski; Jeffrey T. Placker; Holland & Knight LLP(57) **CLAIM**

The ornamental design for a pressure washer pump head, as shown and described.

DESCRIPTION

FIG. 1 is a top-front perspective view of a pressure washer pump head;

FIG. 2 is a bottom-rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines are included for the purpose of illustrating portions of the pressure washer pump head that form no part of the claimed design.

1 Claim, 6 Drawing Sheets(56)
